UNITED STATES PATENT OFFICE.

HARRY D. WILSON, OF JACKSON, MICHIGAN.

CUTTER.

1,055,587.

Specification of Letters Patent. Patented Mar. 11, 1913.

Application filed March 31, 1909, Serial No. 437,047. Renewed July 29, 1912. Serial No. 712,163.

To all whom it may concern:

Be it known that I, HARRY D. WILSON, a citizen of the United States, residing at Jackson, in the county of Jackson and State 5 of Michigan, have invented certain new and useful Improvements in Cutters, of which the following is a specification.

The object of my invention is the provision of a cutter which especially shall be 10 adapted for cutting cabbages into long thin, strips, one of the steps necessary in the manufacture of sauer-kraut, but which may be used for cutting other vegetables or other materials when so desired.

15 My invention consists in certain novelties of construction and combinations of parts as hereinafter set forth and pointed out in the claims.

The accompanying drawings illustrate one 20 example of the physical embodiment of the invention constructed according to the best mode I have so far devised for the practical application of the principle.

Figure 1 is a perspective view of the entire machine. Fig. 2 is a top plan view of the rotary knife carrying disk illustrating the spokes, cover plates and knives, part of the cover plates and knives being removed, and one hopper or feeding device which is 25 suspended above the top surface of the disk. Fig. 3 is a section on line A—A of Fig. 2 enlarged to show the spokes and the relative positions of the knives and cover plates. Fig. 4 is a detail view showing the way of 30 attaching the hub of the disk to the lower end of the vertical shaft. Fig. 5 shows a hopper or feeding device detached. Figs. 6 and 7 are sections on line x—x and y—y of Fig. 5. Fig. 8 is a plan view of a knife removed from the disk. Fig. 9 shows a straight edged knife.

The numeral 1 designates the base piece; 2, a cylindrical housing with an open bottom, the housing being cast integral with the 45 base, and the wall of said housing being disposed at right angles to the base; 3, a cross arm or bridge tree extending from one side to the other of the housing and located slightly below the upper edge of the housing; 4, a bearing at the center of the tree which may be provided with anti-friction balls or rollers; 5, 5, standards or legs bolted to the base at opposite sides of the housing; 6, a cross bar bolted to the top ends of the 50 standards and supported in a horizontal po-

sition above the housing; 7 and 8, bearings at the top surface of the cross bar; 9, a horizontal rotary shaft located in the bearings; 10, a bevel gear wheel at one end of the shaft; 11, a pulley wheel fixed to the shaft; 12, a loose pulley wheel on the shaft; 13, a bearing at the side of the cross bar; 14, a vertical shaft journaled in bearing 13 and bearing 4 at the center of the bridge tree; 15, a bevel gear wheel on shaft 14 and in gear 65 with bevel wheel 10 on the shaft 9, as shown; 16, the rotary knife carrying disk preferably cast in one piece; 17, the hub of the disk, in practice about fifteen inches in diameter; 18, a collar integral with the hub; 19, a hole through the collar and hub; 20, a taper pin passed through holes in the shaft 14 and the collar; 21, set-screws; 22, a collar at the end of the shaft 14 and below the hub 70 removably secured in place by any suitable means; 23, spokes radiating tangentially from the circumference of the hub 17 to the circular rim 24, each spoke being wider adjacent the rim than at the hub so as to present an irregular tapering appearance or 75 shape; 25, the upper horizontal surface of a spoke; 26, the under beveled surface forming a thin edge at one side of a spoke; 27, the vertical edge surface; 28, the open spaces 80 between the spokes; 29, one of the knives 85 with its cutting edge lapping over the edge of an adjacent spoke and raised above the same to form an opening 30, as shown; 31, adjusting screws located within threaded holes in the edge of a spoke and bearing 90 against the under surface of a knife; 32, open slots in a knife; 33, a cover plate located above a knife, the edge 34 being beveled, as shown, and the said plate provided with two series of holes, one series at each 95 edge; 35, a perforated filler strip located under one edge of a cover plate; 36, binding screws passed through the holes at the front edge of the cover plate and the open slots in the knife and seated within threaded 100 holes in and adjacent the edge of a spoke; 37, screws passed through the holes in the rear edge of the cover plate and the holes in the filler plate; 38, the straight edge portion of a knife extending from a to b; 39, the 105 curved edge portion extending from b to c; 40, the half funnel-shaped hopper or feeding device, the same being tapering and curved from end to end, and concavo-convex shaped in cross section, as shown by Figs. 5 110

and 6, so that the space within the same diminishes in depth from the larger to the smaller end thereof; 41, two perforated lugs at the top surface of the smaller end; 42, lugs on the bridge tree; 43, bolts which unite the lugs 41 and 42 and constitute a hinged connection; 44, a perforated lug at the top surface of the larger end of the hopper; 45, a rod with one end threaded and the other 10 perforated and having a bearing for a spring intermediate the ends; 46, a bolt uniting the lug 44 and rod; 47, a perforated lug on the cross bar; 48, a nut on the rod; and 49, a spring on the rod for forcing the funnel or hopper downwardly.

In the drawings Fig. 1 shows only one hopper or feeding device located at one side of the bridge tree, the other one of similar construction being oppositely disposed and 20 the larger end supported by the rod 45 and the smaller end by the lugs 42, the said hopper being removed to show the top surface of the disk. However, one hopper only may be used when so desired.

25 The *modus operandi* is as follows: Rotary motion is imparted to the horizontal shaft, for example, by a belt on the fixed pulley, and through the bevel gears to the vertical shaft 14 and the disk carrying the knives. 30 The cabbages are fed into the larger open end of a hopper, which is suspended with its edges close to the surface of the disk, but not in contact therewith, and as parts of the cabbages are removed by the knives 35 the remaining portions are advanced toward the shallower part of the hopper. In case of a large cabbage or other material being introduced into the hopper the operator can lift the funnel or hopper against the pressure of the spring on the rod and then release it and allow it to fall under the pressure of the spring and the action of gravity. The cut cabbage or other material falls into a receptacle beneath the housing. The under 40 beveled surfaces 26 of the spokes provide open spaces or throats for the cut material and by reason of their shapes the under surfaces of the spokes will not strike the cut strips of cabbage and break them in pieces. 45 The knife edges being of the shape shown, each curved for a part of its length adjacent the hub and then straight to the rim, gives a curved shearing cut near the hub and farther out to the rim a straight edge 50 shearing cut. However, straight edged knives may in some cases be substituted for those shown in connection with the disk.

Obviously, and which is an important and valuable feature of construction, the knives 60 can be adjusted and removed for sharpening and replaced by simply loosening the binding screws; and the cutting edges can be raised or lowered through the medium of the adjusting screws at the edge of a 65 spoke so each knife edge will be in the same

plane whereby the cabbage or other material will be cut to a uniform thickness.

It will be observed that each knife has a beveled surface adjacent to its edge and that the bevel is at the under surface of a knife when the same is in position upon the top of the spoke. The edge of each knife slightly laps over the rear edge of the spoke and cover plate in front of the said knife and the knife edge is slightly raised above 70 the surface of the cover plate and spoke so as to form an opening 30 through which the several pieces or strips of the vegetables being cut or sliced are delivered downwardly. The thickness of the cut slices obviously depends upon the size of the opening 30, which can be varied by the adjustment of screws 31 and screws 36 without removing the screws 37, inasmuch as the cover plate is flexible. Further, it will be observed that the beveled edge of each cover plate is upon the top surface thereof when in position and ends back of the cutting edge of a knife, so there are no projections to engage the vegetables being cut, as the plates slide beneath them. The top of the cutter thus consists of a series of plain surfaces, one edge of each consisting of a knife edge and the opposite edge slightly extended beneath and out of contact with the knife edge at the rear. 80

90 From the foregoing description taken in connection with the drawings it will be clear that I have produced a cutter which will cut cabbages into long thin strips, a form especially desirable for the manufacture of sauerkraut, and which is also adapted for cutting other vegetables, fruits, or other material or materials when so desired. 95

What I claim is:

1. The combination in a machine for cutting cabbages, etc., of a base; a housing; a bridge tree extending from side to side of the housing; a bearing in connection with the bridge tree; standards at opposite sides of the housing; a cross bar supported by the standards; bearings supported by the cross bar; a horizontal shaft journaled in said bearings, said shaft having at one end a beveled gear wheel; a bearing for a vertical shaft in connection with the cross bar; a vertical shaft with a beveled gear wheel at the top end journaled in the bearings on the cross bar and on the bridge tree; means for imparting rotary motion to the horizontal shaft; a disk located below the bridge tree and within the housing and secured to the shaft, said disk having a hub and rim with spokes each with a beveled under surface uniting the hub and rim; and knives secured to the spokes; said shaft and disk being supported and guided by the bearings in connection with the cross bar and bridge tree. 110

120 2. The combination in a machine for cutting cabbages, or other material, and having suitable operating mechanism, of a housing; 125

5 a rotary shaft; a disk within the housing and carried by the shaft; means for supporting the shaft and disk; and a hopper supported above the disk and in a horizontal plane by a hinged connection at one end and by an adjustable rod at the other end.

10 3. The combination in a machine for cutting cabbages, or other material, of a housing; a rotary shaft; a disk within the housing and carried by the shaft; means for supporting the shaft and disk; means for imparting rotary movement to the shaft and disk; and a hopper having a tapering inner surface; a closed top, an opening at one end only for the reception of vegetables and said hopper supported at one end by a hinged connection and at the other end by an adjustable rod having a spring, for the purpose specified.

15 20 4. The combination in a machine for cutting cabbages, or other material, of a housing; a bridge tree; a cross bar; a rotary shaft; a disk within the housing and carried by the shaft; means for supporting the shaft and disk; means for imparting rotary motion to the shaft and disk; and a curved tapering hopper supported above the disk, one end being pivoted to the bridge tree, and the other end movably supported from the cross bar.

25 30 35 5. A disk for a cutting machine having a hub, a rim, spokes uniting the hub and rim, each spoke having an upper horizontal surface and an under beveled surface, a series of knives, each knife having open slots secured to the horizontal surfaces of the spokes, cover plates each with a beveled edge above the knives, and screws for securing the cover plates and knives in place.

40 45 6. A disk for a cutting machine having a hub, a rim, spokes uniting the hub and rim, and knives secured to the spokes; the under surfaces of the spokes being beveled surfaces and one edge of each spoke having a vertical surface, for the purpose set forth.

50 55 7. A disk for a cutting machine having a hub, a rim, spokes between the hub and rim, the under surface of each spoke being beveled, knives secured to the upper horizontal surfaces of the spokes, cover plates above the knives, and screws for securing the knives and cover plates in position, the edge of each cover plate adjacent the knife edge being beveled.

60 65 8. The combination in a cutting machine, of a housing, a bridge tree secured to the housing, a bearing on the bridge tree, a cross bar, a bearing on the cross bar, a shaft journaled in the bearing on the bridge tree and the bearing in connection with the cross bar, a disk with open slots and knives secured to the shaft, and a hopper supported by the bridge tree and the cross bar in a horizontal position above the top surface of the disk.

65 9. The combination of a disk having a

hub, a rim, and spaced spokes uniting the hub and rim so as to form open spaces between the spokes; cover plates, each having a beveled edge and secured to the top surface of a spoke; knives, each having one edge located between a cover plate and a spoke with its opposite cutting edge extended so as to slightly overlap and occupy a position out of contact with the rear edge of a cover plate upon the spoke in front of the knife; and means for detachably securing the knives in fixed positions so as to provide open spaces 30 between the knives at their cutting edges and the top surfaces of the cover plates.

70 75 80 85 90 95 100 105 110 115 120 125 130 10. The combination of a disk having a hub, a rim, and spaced spokes uniting the hub and rim so as to form open spaces between the spokes; cover plates, each having a beveled edge and secured to the top horizontal surface of a spoke; knives, each having one edge located between a cover plate and a spoke with its opposite cutting edge extended so as to slightly overlap and occupy a position out of contact with the rear edge of a cover plate upon the spoke in front of the knife; means for detachably securing the knives in fixed positions so as to provide open spaces 30 between the knife edges and the top surfaces of the cover plates; and means for adjusting the cutting edges of the knives and the edges of the cover plates to widen or narrow the open spaces 30 between the knife edges and the top surfaces of the cover plates adjacent to the knife edges.

10. The combination of a disk having a hub, a rim, and spokes uniting the hub and rim to form open spaces between the spokes; cover plates, each having one edge beveled, secured to the top surfaces of the spokes; knives, each with a beveled surface adjacent the cutting edge, located between the cover plates and spokes, the cutting edge of each knife extended and overlapping and out of contact with the rear edge of a cover plate adjacent thereto to form open spaces 30; means for securing the knives and the edges of the cover plates above them to the spokes; and set-screws engaging the spokes and the under surfaces of the knives for adjusting the edges of the knives relative to the edges of the cover plates adjacent thereto.

11. The combination of a disk for a slicing machine having a hub, a rim, and spokes uniting the hub and rim to form open spaces between the spokes; knives, each with a beveled surface adjacent the cutting edge, detachably secured to the top horizontal surfaces of the spokes so the cutting edge of each knife and the beveled surface thereof will slightly overlap and occupy a position out of contact with and above the top surface of a spoke adjacent thereto, thus forming open spaces 30; and means for adjusting and holding the cutting edges of the knives at different distances above the top

surfaces of the adjacent spokes for varying the size of the open spaces 30, in substance as set forth.

13. The combination of a disk for a cutting machine having a hub, a rim, and spokes uniting the hub and rim so as to form open spaces between the hub and rim; perforated filler strips 35; perforated cover plates 33 with beveled edges 34; screws 37 10 securing the cover plates and filler strips to the top surfaces of the spokes; knives 29 between the spokes and cover plates, the cutting edge of each knife overlapping but out of contact with the surface of a cover plate 15 adjacent thereto; and screws for adjustably securing the knives and the edges of the cover plates above the knives to the top surfaces of the spokes.
14. The combination of a disk having a hub, a rim, and spokes uniting the hub and rim, said spokes fashioned so as to provide curved open spaces between them; cover plates with curved edges, the surface adjacent one edge being beveled, secured to the 20 tops of the spokes; knives, each with a curved edge, located between the top surfaces of the spokes and the under surfaces of the cover plates; and means for detachably and adjustably securing the knives in 25

position; the curved edge of each knife 30 overlapping the oppositely curved edge of a cover plate adjacent thereto and being slightly raised above the top surface of said plate to form openings 30 for the passage of the cut or sliced material. 35

15. The combination of a disk for a cutting machine having open slots therein radiating from the center of the disk to points adjacent the rim; cutting knives detachably secured in a circular series to the top surface of the disk, the knives being so disposed that the cutting edge of each knife slightly laps over an opening in the disk and is slightly raised above the surface of the disk which bounds the edge of a slot so as to 40 form open spaces 30 between the cutting edges of the knives and the top surfaces of the disk adjacent the slots; and means for adjusting and holding the cutting edges of the knives so as to vary the size of the openings 30 uniformly throughout the series and beneath the knife edges. 45

In testimony whereof I affix my signature in presence of two witnesses.

HARRY D. WILSON.
